UNITED STATES PATENT OFFICE.

DAVID LEVIGTON, OF NEW YORK, N. Y.

DISPLAY CARD AND INSERT FOR BOXES.

Application filed July 14, 1922. Serial No. 574,967.

To all whom it may concern:

Be it known that I, DAVID LEVIGTON, a citizen of the United States, and a resident of New York, in the county of New York and State of New York, have invented certain new and useful Improvements in a Display Card and Insert for Boxes, of which the following is a full, clear, and exact specification.

10 This invention relates more particularly to a class of devices adapted to be used in conjunction with boxes.

My invention has for its object primarily to provide a card and insert designed to be 15 removably applied interiorly of a box or like container for partitioning the body of the box into compartments so that goods of different colors or articles of various kinds may be kept and displayed for sale without 20 liability of the articles in their respective compartments being accidentally mingled with the articles of the other compartments, and which is also of a form including a flap member adapted to permit advertising matter or goods to be displayed 25 thereon, the invention contemplating dispensing with the requirement of providing separate display cards and fastening within the box separate partition members as 30 is incident to present methods. The invention consists essentially of a body with a bottom member having upwardly protruding spaced partition members so that when the body is removably inserted in the body 35 of a box or other container its interior will be divided into separate compartments, and extending from the bottom member is a flap adapted to be foldably swung from upstanding position inwardly and outwardly of the 40 box toward and from the partitions, all of which are folded from a blank cut from a single sheet of material.

A further object of the invention is to 45 provide a display card and insert for boxes of a simple and efficient form which may be made of appropriate material in any size and shape.

With these and other objects in view, the 50 invention will be hereinafter more fully described with reference to the accompanying drawing forming a part of this specification in which similar characters of reference indicate corresponding parts in all the views, and will then be pointed out in the 55 claim at the end of the description.

In the drawing, Figure 1 is a plan of

the blank for making one form of display card and insert embodying my invention, and

Fig. 2 is a fragmentary view, partly 60 broken away, showing a perspective of the device applied to a box.

The device or display card and insert has a body portion 10 and a flap member 11 adapted to be foldably swung to and from 65 upstanding position toward and from the body portion 10. The parts of the device may be of any appropriate size and shape, though the body portion of the device illustrated is substantially rectangular to allow 70 of being removably inserted in the body, as A, of a box B or other container for holding merchandise and other articles, and the box may be provided with a lid C.

The body portion 10 and the flap member 75 11 of the device are preferably formed from a blank, as 12, which is cut, scored and folded from a single sheet of card board or other appropriate foldable material. The body portion 10 may include two flange 80 members or side walls 13, 14 and a bottom or base member 14^a which are provided by scoring, as at 15, the blank lengthwise in spaced proximity to its free side edge, and by scoring the blank, as 16, at the inse- 85 cision of the body portion 10 with the flap member 11, as well as scoring the blank lengthwise, as at 17, lengthwise in spaced proximity to scoring 16. When the blank is folded on the scorings 15 and 17 accord- 90 ingly the flange members or side walls 13 and 14 will be disposed rightangularly up- 95 ward from the bottom member 14^a, and by making these parts of the body portion of proper sizes they will closely fit removably in the body A of the box B when inserted therein, as shown in Fig. 2, so that the bottom member 14^a will rest upon the bottom 100 of the body of the box, while the flange members 13, 14 are disposed against the side walls of the body of the box.

The device is employed for providing separate compartments in the box by the body portion 10 of the device being divided into compartments, as 18, 19, 20, 21 through the 105 provision of partition members, as 22, 23, 24. These partition members are formed by slitting spaced parts of the bottom 14^a of the body portion 10 crosswise, as at 25, 26, 27, and each slit is somewhat the shape of 110 an extended U of a length so that the ends of all the slits terminate at the scorings 15

2
and 17 of the blank 12. The arms of the U-shaped slits are of lengths corresponding approximately to the widths of the flange members 13 and 14 of the body portion 10, 5 and the blank is transversely scored, as at 28, 29, 30, at the free ends of the arms of the U-shaped slits. By folding on the scoring 28, 29, 30 the portions of the bottom or base member 14^a of the body portion 10 between 10 the U-shaped slits in upwardly direction similar to the flange members 13 and 14 the partition members 22, 23, 24 will be formed to provide the compartments 18, 19, 20, 21 for holding merchandise of different 15 colors or articles of various kinds so that the articles of one compartment will not accidentally become mixed with the articles of the other compartments.

By flexing the blank 12 at its scoring 16 20 the flap member 11 may be foldably swung from upstanding position above the body portion 10 toward and from the partition members 22, 23, 24 to allow the lid C of the body A of the box to be closed, and this 25 flap member may be cut in a fanciful shape if desired to serve as a card for displaying thereon advertising matter, as at 31, or this flap member may also be used to display articles by being detachably mounted there- 30 on.

In the foregoing description, I have embodied the preferred form of my invention,

but I do not wish to be understood as limiting myself thereto as I am aware that modifications may be made therein without departing from the principle or sacrificing any of the advantages of this invention, therefore, I reserve to myself the right to make such changes as fairly fall within the scope thereof. 35 40

Having thus described my invention, I claim as new and desire to secure by Letters Patent:

An insert for boxes, cut and folded from a single blank, comprising a substantially 45 rectangular body part having its side edge portions flexed lengthwise to provide upstanding side walls for removably fitting the interior of a box and the body part having in its central portion between the side walls 50 spaced substantially U-shaped slits with the portions of the body part within the slits being bent upwardly in spaced parallel relation providing partition members, and a display flap extending from one of the side 55 walls for being foldably disposed toward and from the partition members.

This specification signed and witnessed this 13th day of July A. D. 1922.

DAVID LEVIGTON.
